(57) **CLAIM**

The ornamental design for a shelf bracket, as shown and described.

DESCRIPTION

FIG. 1 is a perspective view of a shelf bracket, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken line showing of the support arms is for the purpose of illustrating portions of the shelf bracket that form no part of the claimed design.
